UNITED STATES PATENT OFFICE.

DAVID H. SPEER, OF PITTSBURG, PENNSYLVANIA.

SWITCH-LOCK.

SPECIFICATION forming part of Letters Patent No. 276,089, dated April 17, 1883.

Application filed July 14, 1882. (No model.)

To all whom it may concern:

Be it known that I, DAVID H. SPEER, of Pittsburgh, in the county of Allegheny and State of Pennsylvania, have invented a new and useful Improvement in Railroad-Switch Locks, of which the following is a full, clear, and exact description, reference being had to the annexed drawings, forming part of this specification.

This invention relates to locks for securing the lever or bar by which a railroad-switch is operated; and the invention consists in a spring-actuated bolt of peculiar construction, combined with devices for setting the same in such manner that it will be tripped by the disengagement of the lever and thrown into position for automatically locking said lever.

In the drawings, Figure 1 is a longitudinal section on line *x x*, Fig. 2, showing the key in position for unlocking or setting the bolt. Fig. 20 2 is a plan view with the top of the casing removed, showing the lever partially broken away; and Fig. 3 is a sectional view taken on line *y y*.

The casing of the lock is formed of two shells, A B, having a cylindrical recess, C, for receiving the bolt D, which is provided with a collar, E, to limit its outward movement. The inner end of the bolt is reduced at F and squared to form a sliding joint with the cylindrical head G, which contains a seat for a portion of the key H. The head G is supported in suitable bearings, and is provided with a collar, I, which is accommodated in a recess, J, in the casing. A corresponding head, K, is supported in the end of the casing, and is provided with a collar, L, which limits its outward movement. The head K is provided with a key-seat, M, through which the key H passes to engage with the seat in the head G. The object of forming the key-seat in the two separate heads is to enable the key to be withdrawn as soon as the bolt is unlocked without having to turn it back, and also, in case the lug *h* on the key should be wrenched off, to allow it to drop down between the heads into the recess J, where it will be out of the way, so that another key can be used without the necessity of opening the casing to remove the said lug.

The bolt D is inclosed by a coil-spring, N, one end of which is secured to the bolt, while

the other engages with a recess, O, in the lower shell, B. The bolt, near its inner end, is provided with a lug, P, which engages with the surface of the upper shell, A, to prevent the bolt from being turned the wrong way, and which is adapted to be turned with the bolt in the direction of the arrow until it passes the end of a spring, Q, located underneath it in the recess J', and is held thereby. As shown 60 in Fig. 2, the upper end of this spring is narrower than the recess J', so that if the bolt is pressed inward longitudinally against the tension of the coil-spring the lug P will thereby be thrown out of engagement with the spring 65 Q, and the coil-spring, which has been wound by the turning of the bolt, will retract the bolt and lug P to the position shown in Fig. 3.

As shown in Figs. 1 and 2, the outer end of the bolt D is beveled at R to form a nose, S, at 70 its lower side, which shall engage with a perforation in the lever T to hold the lever in a locked position. When the key is applied and the bolt is turned half a revolution in the manner above described, the nose S is turned up to 75 the position shown in dotted line, Fig. 1, in which position it is held by the mechanism already described until the lever T is lifted upward out of the seat or rest formed for it between the casing and the projection U. As 80 the lever is lifted upward, (see Fig. 1,) it will bear against the beveled surface of the end of the bolt and press the latter inward to make its escape, while the inward movement of the bolt releases the lug P from the spring Q, and 85 thus trips said mechanism and allows the bolt to turn back to its normal position, with its nose downward, (see Fig. 1,) in which position it will engage with the lever automatically by simply pressing the lever down against the 90 bevel surface of the said end, the coil-spring yielding and allowing the necessary longitudinal movement of the bolt.

It is evident that, instead of the ordinary ground-lever for operating the switch, a longitudinally-moving bar connected to the switch may just as well be used in connection with this lock, provided the normal position of the bolt be changed, so that the bevel end thereof shall be operated upon by a horizontally-moving part instead of a vertically-moving one, as above described.

Having thus described my invention, what I claim, and desire to secure by Letters Patent, is—

1. The combination, with the operating lever or bar of a railroad-switch, of the spring-actuated bolt and means for setting the bolt, whereby it may be tripped by the disengagement of the lever and restored to a position for automatically locking said lever, substantially as shown and described.

2. The combination, with the operating lever or bar of a railroad-switch, of the bolt having

its projecting end beveled on one side, the coil-spring inclosing the bolt, the key-seat formed in two separate parts, one of which engages with the bolt with a sliding joint, and the spring adapted to engage with a lug on the bolt to hold it set for releasing the lever, substantially as shown and described.

DAVID H. SPEER.
